MENDEL OSNOS, OF BERLIN, GERMANY, ASSIGNOR TO TELEFUNKEN GESELLSCHAFT FUR DRAHTLOSE TELEGRAPHIE M. B. H., OF BERLIN, GERMANY, A CORPORATION OF GERMANY

OSCILLATION GENERATOR

Application filed October 1, 1929, Serial No. 396,445, and in Germany September 27, 1928.

An application for this invention was filed in Germany September 27, 1928.

It is known that disturbances due to the action of fading can be eliminated in radio communication work on short waves by sending out simultaneously two or more carrier waves which differ relatively little from each other.

For this purpose the assumption is made that the two carrier frequencies, prior to being fed to the amplifier stage, are produced by separate generators.

Now, according to the present invention the foregoing scheme is simplified in that, for the production of two or more frequencies, a common or joint tube generator is employed whose oscillation circuits, especially the grid circuits, are designed for two or more waves in accordance with the number of frequencies to be generated.

The accompanying drawing exemplifies the present invention.

For example, as illustrated in the drawing, the grid circuit of a tube oscillator can be made distinctly triple-wave by the series connection of a tuning capacity C and two oscillation circuits I and II.

The three frequencies generated by the present oscillator are determined by the resonant frequencies of the two tuned circuits I, II and the third tuned circuit comprising the tuning condenser C in conjunction with the two tuned circuits I and II.

I claim as my invention:

A generator for producing simultaneously a plurality of carrier waves of slightly different frequencies comprising an electron discharge device, and an input circuit therefore comprising a plurality of parallel tuned circuits tuned to different frequencies, serially connected together, and, a tuning condenser connected in series with the tuned circuits.

MENDEL OSNOS.
